(57) **CLAIM**

The ornamental design for a display screen or portion thereof with graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a display screen or portion thereof with a graphical user interface showing our new design according to a first embodiment;

FIG. 2 is a front view of a display screen or portion thereof with a graphical user interface showing our new design according to a second embodiment;

FIG. 3 is a front view of a display screen or portion thereof with a graphical user interface showing our new design according to a third embodiment;

FIG. 4 is a front view of a display screen or portion thereof with a graphical user interface showing our new design according to a fourth embodiment;

FIG. 5 is a front view of a display screen or portion thereof with a graphical user interface showing our new design according to a fifth embodiment;

FIG. 6 is a front view of a display screen or portion thereof with a graphical user interface showing our new design according to a sixth embodiment;

FIG. 7 is a front view of a display screen or portion thereof with a graphical user interface showing our new design according to a seventh embodiment;

FIG. 8 is a front view of a display screen or portion thereof with a graphical user interface showing our new design according to an eighth embodiment;

FIG. 9 is a front view of a display screen or portion thereof with a graphical user interface showing our new design according to a ninth embodiment; and,

(Continued)

FIG. 10 is a front view of a display screen or portion thereof with a graphical user interface showing our new design according to a tenth embodiment.

The broken lines in FIGS. 1-10 show portions of a display screen or portion thereof with a graphical user interface which form no part of the claimed design. The heavy weight dashed lines in FIGS. 2, 4, 6, 8 and 10 form part of the claimed design.
